UNITED STATES PATENT OFFICE.

GEORGE F. McCHEY, OF PROVIDENCE, RHODE ISLAND.

CARRIER FOR BRAIDING-MACHINES.

1,267,240.

Specification of Letters Patent. Patented May 21, 1918.

Application filed November 23, 1916. Serial No. 132,958.

To all whom it may concern:

Be it known that I, GEORGE F. McCHEY, a citizen of the United States, and resident of the city of Providence, in the county of 5 Providence and State of Rhode Island, have invented certain new and useful Improvements in Carriers for Braiding-Machines, of which the following is a specification.

This invention relates to an improvement 10 in carriers for braiding machines, and the primary object of the invention is to provide a stop on the top of the standard to positively prevent the top weight or latch from being accidentally thrown from the 15 standard even while the carrier is running at a high velocity.

A further object of the invention is to leave one side of the standard straight to its upper end and cut away on its opposite 20 edge for a short distance downward from its upper end whereby this latch may be applied to the standard at a point below the upper stop lug by a laterally rotating motion.

25 The invention further consists in the provision of a bottom or tension weight also 30 slideable on the standard provided with a finger or extension for engaging a portion of the top latch to prevent the latter from rotating on the standard when both are in raised position.

It is found in practice that where the top 35 latch is passed onto the standard over the end thereof, that the short laterally extending boss must be so small that it fails to serve as a positive stop to prevent the latch from being thrown off therefrom in the same direction it was applied, thereby eliminating the traveling speed of the carrier.

40 To obviate this serious difficulty and prevent the latch from being thrown upward off the end of the standard, I have cut away the side of the standard to permit this latch to be passed onto the standard by a lateral 45 rotary motion and then I provide means on the bottom or tension weight for preventing the latch from rotating on the standard when in raised position.

A further advantage of my improved construction is that the latch is provided with a continuous or unbroken bearing on the 50 yarn on the spool, the cut away portion of the standard being on the opposite side or the side which does not receive the strain.

55 With these and other objects in view, the invention consists of certain novel features

of construction, as will be more fully described, and particularly pointed out in the appended claims.

In the accompanying drawings: 60

Figure 1— is a side elevation showing my improved standard with a spool mounted on the spindle and the tension weight and latch mounted on the standard, the weight being in the down position.

Fig. 2— illustrates the bottom weight as having been raised to engage and raise the latch, also showing the finger on the tension weight engaging the boss on the latch to prevent the latter from rotating while in raised 70 position.

Fig. 3— is a view of the rear side of the standard showing the one edge cut-away, and representing the latch in dotted lines 75 as being applied to the standard.

Fig. 4— is a rear view of the latch showing the lateral extension thereof designed to be engaged by the projection on the bottom weight to prevent rotation of the latch.

Fig. 5— is a plan view showing the standard in section on line 4—4 of Fig. 2 through the reduced portion thereof, also representing the latch in the act of being applied to the standard at its reduced point by a lateral rotating motion, the end of the spool 85 also being shown.

Fig. 6 is a rear view of the bottom or 90 yarn tension weight.

Referring to the drawings, 10 designates the carrier frame having a groove 11 adapted to be run and be guided in the usual race-way, said carrier frame being also provided with a spindle 12 on which a yarn spool 13 is mounted. The upper end or head of the spool 14 is provided with the 95 usual ratchet teeth 15.

This carrier frame is provided with a standard 16 having the usual lead eye 17 in its upper end and a guide eye 18 near its middle portion. The standard is also 100 provided with an exceptionally large forwardly projecting stop or lug 19 at its upper end.

Another feature in the construction of the standard is that it is provided with one 105 straight edge 20 extending up to this guide eye and lip while its opposite edge at 21, see Figs. 3 and 5, is cut away for a short distance downward to provide a narrow neck portion for the purpose of permitting the 110 tension weight 22 and also the latch 23 to be positioned thereonto.

An essential feature of my invention is that the stop lip 19 is formed of a size so large that the latch cannot be passed thereover onto the standard for the reason that 5 when the carrier is running at a high rate of speed the tension weight is thrown with great force against the latch which drives it hard against this stop, and great trouble has been experienced with the old style carrier, where the latch is applied over the end of the standard in throwing the latch over the lip, in which case the latch is so long in returning that it permits the spool to rotate several teeth and so allows the bottom 10 weight to drop sufficiently to engage the stop lever and stop the machine, but by my improved construction this stop lug is so large that it must positively engage and limit the upward motion of this latch. 15 Therefore in order that so large and positive a stop may be used, I am obliged to apply the latch to the standard at a point below the top, which is accomplished by hooking one edge 23 of the latch around the straight 20 edge of the standard as illustrated in Fig. 25 and then to swing the opposite edge 24 around through the cut-away portion of the standard after which it is permitted to slide down the standard into position to permit 30 its tongue 25 to engage the ratchet teeth 15 on the spool.

In order to positively prevent this latch from rotating back again in the direction to release itself while running, I have formed 35 a laterally extending boss 26 on one edge thereof and I have also provided a finger or upwardly extending member 27, on the upper end of the tension weight 22, which finger is adapted to hook over or around the 40 boss 26 when the weight is raised so as to positively prevent rotation of this latch when in raised position as illustrated in Fig. 2.

I have shown and described one means by 45 which this top latch may be prevented from rotating while in its up position but there are many ways of accomplishing this object and any suitable means may be employed for this purpose for preventing such rotat- 50 ing motion.

Another feature which is of importance is that the straight side edge of the standard produces a full length bearing for the working edge of the latch, even when thrown upward and out of engagement with the spool. 55 This is not the case with the usual standard which is cut away on both of its edges.

Having thus described one illustrative embodiment of my invention I desire it to be 60 understood that I do not wish to limit myself to the exact construction shown and described as the details may be changed

without departing from the spirit of my invention, the scope of which is defined by the appended claims.

65

I claim:

1. A braider carrier comprising a frame having a standard with longitudinally-disposed guiding edges, a yarn tension weight slidable on said standard, a latch having 70 grooved edges with guiding flanges to slidably engage the guiding edges of said standard, a head on the free end of said standard of a size to prevent the passage of the latch thereover, a section of one edge of said 75 standard immediately below said head being removed substantially equal to the length of said guide flange on the corresponding edge of the latch whereby said latch may be connected to and disconnected from said standard by a rotating motion only, and means for preventing accidental disengagement of said latch from said standard when carried upward by said tension weight.

2. A carrier for braiding machines comprising a frame having a spool spindle and a standard, a sliding latch on said standard for engaging teeth on the spool, a lateral extension on the body of said latch, a yarn tension weight also slidable on said standard, a stop lug on the standard of a size to prevent the latch being removed over the end thereof, one edge of said standard being straight to provide a bearing for the latch to the top of its stroke, said standard being 95 reduced on its opposite edge to permit the latch to be applied thereto at a point below said stop with a rotating motion, and an upward extension on one edge of said weight to engage said lateral extension on the latch 100 to prevent an unlocking rotative movement of the latter when both are raised.

3. A carrier for braiding machines comprising a frame having a spool spindle and a standard, a sliding latch on said standard 105 for engaging said spool, a yarn tension weight also slidable on said standard, a stop at the end of said standard to prevent the latch from being thrown or otherwise removed thereover, one edge of said standard 110 being straight and its opposite edge cut away at a point just below said stop to permit ready application of the latch to the standard by a lateral rotary motion, and an upwardly extending portion on said tension 115 weight engaging said latch to prevent a rotative motion of the latter when the two are in raised position.

In testimony whereof I affix my signature in presence of a witness.

GEORGE F. McCAYEY.

Witness:

HOWARD E. BARLOW.
